UNITED STATES PATENT OFFICE.

ALBERT T. VAN ALSTYN, OF GRAND RAPIDS, MICHIGAN.

SEPARABLE BUCKLE.

1,357,662.

Specification of Letters Patent.

Patented Nov. 2, 1920.

Application filed October 13, 1915. Serial No. 55,598.

To all whom it may concern:

Be it known that I, ALBERT T. VAN ALSTYN, a citizen of the United States, residing at Grand Rapids, in the county of

5 Kent and State of Michigan, have invented certain new and useful Improvements in Separable Buckles, of which the following is a specification.

The present invention relates to a separable buckle particularly characterized by the fact that it comprises two co-acting parts automatically assembled by a strap used in connection therewith, the said buckle being more especially adapted for suspenders, garters, and in fact any type of limb or body encircling article wherein it is required to adjust the article in size or length to conform to the requirements of the wearer.

20 To this end the objects of the present invention may be generally stated as comprehensive of a buckle of the above mentioned character which is simple in construction, and therefore cheap to manufacture, easy 25 to assemble and thread, and when in use, does not wear upon the material of which the article, to which the buckle is attached, is made.

Specifically speaking, one object is to so 30 associate and secure the strap tensioning lever of the buckle to the strap end that an enormous saving of material is effected when manufacturing the articles in large quantities; and furthermore, by reason of 35 the manner in which said strap end and strap tensioning lever are connected, said strap end being disposed within the tension bar of the tensioning lever, a saving of space is accomplished due to the fact that 40 this construction results in only two thicknesses of strap, whereas in the case of the usual buckle three thicknesses of strap are necessitated by reason of the fact that the attaching end of the strap is looped back 45 on itself and either sewed or riveted to the buckle.

Another object, of one principal embodiment of my invention, resides in the fact that the strap end is attached to the strap 50 tensioning lever while the latter is entirely free of the buckle frame, and the two separate parts of the buckle, namely the frame and tensioning lever, are so constructed and formed that the buckle may then be assembled with exceptional ease by hand, it being only necessary to merely thread the free

end of the strap through the frame aperture, thus forming what may be most appropriately termed a separably mountable two-part interlocking buckle. 60

A further object consists in the manner of buckling the strap which is accomplished by providing the strap tensioning lever with a hollow tensioning bar having a smooth rounded face and which is movable to displace a holding length of the full width of the strap through the frame without recourse to prongs or tongues, which must of necessity mutilate the strap, and yet the holding power of the buckle is positive. 65 70

A still further object resides in so associating the strap tensioning lever and the frame of the buckle that, when it is desired to adjust the strap, the active face of the tensioning lever is moved entirely out of 75 and below the normal plane of the strap and thus permits the latter to slide freely without resistance between the frame and said face.

Yet another object rests in constructing 80 the buckle in such a manner that, when it is in use, no metal surface whatsoever is in contact with the skin, thereby producing a buckle of rustless construction.

Still another object consists in arranging 85 the strap tensioning lever relative to the frame and strap so that the tendency, when in use, is to maintain the tensioning lever in a positively locked or buckled position and thereby hold the strap against slipping. 90

One other object lies in producing a buckle of such construction that it is substantially flat and adds little to the thickness of the actual dimensions of the overlying straps with which the buckle is used and thus reduces, to a minimum, the wear on any garments working over the top of the buckle. 95

With the above, and other objects in view, I will now proceed to describe a preferred form, and various modifications, of this invention which I have found in practice to give good results, and which I have accordingly illustrated in the accompanying drawing: 100

Figure 1 is a top plan view showing the 105 two-part separable buckle, of the preferred form, assembled.

Fig. 2 is a view, in perspective, of the strap tensioning lever used in connection with the buckle shown in Fig. 1, properly 110 swaged to the strap end.

Fig. 3 is a detail view, in plan, of one end

of the buckle frame showing the manner of forming the fulcrum pockets.

Fig. 4 is a sectional view on the line 4—4 of Fig. 3.

5 Figs. 5 and 6 are sectional views on the line 5—5 of Fig. 1, showing the buckle in the unbuckled and buckled positions, respectively.

Fig. 7 is a plan view of a modified construction.

Fig. 8 is a sectional view on the line 8—8 of Fig. 7, showing the buckle in the unbuckled position.

Fig. 9 is an end elevation of the buckle shown in Figs. 7 and 8, but showing the same in the buckled position.

Fig. 10 is a view, in perspective, of the tensioning lever of another modified form.

Fig. 11 is an end elevation of a buckle including the tensioning lever shown in Fig. 10.

Fig. 12 is a sectional view on the line 12—12 of Fig. 10.

Fig. 13 is a plan view of one side of another modified form of tensioning lever showing the manner of securing the strap end thereto.

Fig. 14 is a plan view of the reverse side of the tensioning lever shown in Fig. 13; and

Fig. 15 is a sectional view on the line 15—15 of Fig. 14.

In detail:

With particular reference to Figs. 1 to 6 inclusive, wherein the preferred form of my invention is illustrated; the buckle is of separable construction and comprises the frame 1 which may be of thin metal slightly bent down on the side edges, as shown at 2, 40 to stiffen the frame, and provided with the substantially rectangular frame aperture 3, of such width that it easily accommodates the width of the strap to be used with the buckle. At each end of the frame aperture 3, and offset from the center line thereof and also directly in alignment with each other, are the fulcrum pockets 4, which receive the pintles 5 carried at each end of a strap tensioning lever 6, which includes the tensioning bar 7 substantially at right angles to the lever portion 8 and which is offset with respect to the pintles 5. The tensioning bar 7 is formed by turning over a portion of the metal of which the tensioning lever is formed and in so doing one end of a strap 9 is swaged therein as shown in Figs. 2, 5 and 6, thus requiring only an extremely small amount of material to secure the strap to the tensioning lever 6, and also forming a closed rounded strap engaging face 10 of smooth contour and substantially the width of the strap. In order to securely retain the strap end one edge of the turned over portion of the tensioning bar carries 65 teeth 11, and since a part of the lever portion

8 is struck out as at 12, and is formed into teeth, the strap is securely engaged throughout substantially its entire width and thus cannot pull away from the tensioning lever.

As before stated, the fulcrum pockets 4

70

are offset and furthermore they are deep enough so that when the buckle is assembled, as shown in Figs. 1, 4, 5 and 6, the

75

pintles 5 are located below the normal plane of a strap passing between the tensioning

75

bar 7 and the frame 1 and also, due to the

78

offset of the pintles 5 with respect to the tensioning bar 7, the latter, when the buckle

80

is in an opened position, lies in a plane below the plane of such strap positioned be-

80

tween the frame 1 and tensioning bar.

Then when the buckle is in the closed position, the engaging face 10 of the tensioning

85

bar 7 projects a holding length of the entire width of the strap through the aperture

85

3 of the frame 1, as shown in Fig. 6, and the

88

strap is thereby securely held in an ad-

90

justed position. In the use of the buckle on suspenders, garters and the like, the

90

free end of the strap will, of necessity, be looped back underneath the portion 8 of

95

the lever 6 and thence returned over the

95

top of the same and passed between the

98

frame and tensioning bar 7 (see Figs. 5 and

100

6), thus the lever 6 automatically is main-

100

tained in assembled relation with respect to

105

the frame by means of the strap and only

110

two thicknesses of strap are necessitated

115

due to the fact that the tensioning bar 7

120

carries one end of the strap.

Furthermore, when the buckle is in the

125

unbuckled position the strap may be easily

130

threaded through the same because of the

135

large spaces left at A and B since the

140

tensioning bar 7 will then be below the nor-

145

mal plane of the strap when passed through

150

the buckle.

In other buckles it is necessary, when

155

buckling and unbuckling the same, to uti-

160

lize a lever located on the top of the strap

165

and which carries teeth, and thus when the

170

buckle is buckled this lever projects out-

175

wardly at an uncomfortable angle for the

180

wearer. Now, the present buckle may be

185

unbuckled by simply tipping the frame 1

190

in the proper direction, or inserting the

195

finger between the overlapping straps and tip-

200

ping the portion 8, of the tensioning lever,

205

which will then throw the tensioning bar 7

210

to a position entirely free from that por-

215

tion of the strap between it and the frame

220

and the strap will then slide easily therebe-

225

tween for adjustment.

Referring to Figs. 7, 8 and 9, the buckle

230

therein illustrated is similar to the buckle

235

hereinbefore described in that it is of two-

240

part construction and operates in the same

245

manner. However, instead of forming the

250

frame 1 as shown in Fig. 1, the frame 11^a

255

of this buckle may be bent down into ears

260

12^a at each end which are apertured as shown at 13 to receive the pintles 14 of the strap tensioning lever 15. The tensioning lever 15 is formed with the portion 17 bent back at right angles to the main portion and provided with teeth and one end of a strap 18 is secured thereunder and wrapped over the top to form the tensioning bar. Thus the active face of the tensioning bar 10 and lever is formed with a smooth surface of the material of which the strap is made. Otherwise the operation of the buckle is the same as that described in connection with Figs. 1 to 6 inclusive.

15 A similar manner of attaching the strap end to the tensioning lever is employed in Figs. 10 to 12, wherein a portion of the tensioning lever 19 is bent at right angles as shown at 20 and carries the pintles 21. 20 Also, formed on the edge of the portion 20 are the teeth or spurs 22 which are pushed through the end of the strap 23 which is then wrapped around the portion 20 and forms the active face of the tensioning 25 lever. In Figs. 13 to 15 inclusive a somewhat more simple construction of tensioning lever is shown, in which the tensioning lever includes the channel formed by the parallel sides 24, one having teeth, and between which the end of a strap 25 is swaged, while the lever portion 26 is struck up therefrom.

In any of the foregoing constructions it will be evident that the buckle is purely of 35 separable construction in that it consists of only two parts, namely, the frame and the tensioning lever, and, due to the peculiar arrangement of the strap in connection with the tensioning lever of each form, the 40 metal parts of each buckle are entirely protected against contact with the skin of the wearer, thus producing a rustless construction.

Furthermore, as emphasized in the pre- 45 lude to the specific description, the arrangement of the buckle parts and strap, as well as the construction, is such that the buckle is far thinner than the usual buckles and, in fact while the parts in most of the 50 views are exaggerated to a certain degree, the buckle shown in Fig. 11 might be taken as representative of the dimensions of the buckle in actuality.

While, in the foregoing specification, and 55 in the drawing, I have illustrated certain specific embodiments of my invention which I have found by the use of actual working models to be practical and give good results, I do not wish to limit myself to such constructions but may resort to various modifications which fall within the scope of my invention as defined in the appended claims.

I claim:

1. A separably mountable two-part interlocking buckle, including an apertured

frame provided with oppositely alined fulcrum pockets extending below said frame, a strap tensioning lever having pintles fulcrumed in said pockets and comprising a tensioning bar bent upon itself to grip one 70 end of a strap, the portion gripping the strap forming a rounded edge adapted to engage said strap when passed between the lever and frame, and the lever moved to operative position.

2. A separably mountable two-part interlocking buckle, including an apertured frame provided with oppositely alined fulcrum pockets extending below said frame, a strap tensioning lever having pintles fulcrumed in said pockets and comprising a tensioning bar bent upon itself to grip one 80 end of a strap, the portion gripping the strap forming a rounded edge adapted to engage said strap when passed between the lever and frame, and the lever moved to operative position, said pockets being of a width greater than the thickness of the pintles whereby the pintles will have a sliding movement laterally of said pockets 90 when the lever is in closed position.

3. A separably mountable two-part interlocking buckle, comprising a frame having a strap receiving aperture and oppositely alined fulcrum pockets, the upper face of 95 the depressed portion of said pockets extending below the lower face of said frame, a lever having pintles fulcrumed in said pockets and comprising a strap tensioning bar offset from said pintles, whereby when 100 the lever is in open position a strap may have free sliding movement between the end of the lever and the lower face of the frame, and when in closed position, said bar will crimp the strap in said aperture, said strap 105 tensioning bar having a groove for gripping the end of a strap whereby the strap may pass around the lever and back through the aperture of the frame and overlie said lever to normally hold it in locked position 110 when the buckle is in use.

4. A separable and instantly mountable two-part buckle comprising an apertured frame having a strap receiving aperture and oppositely alined fulcrum pockets, a 115 lever having pintles fulcrumed in said pockets and comprising a tensioning bar bent upon itself to grip the end of a strap and form an edge for crimping the strap in the aperture of the frame when passed 120 therethrough, whereby the strap may pass around the lever and the latter lie between two thicknesses of the strap and be normally held in locked position when the buckle is in use.

5. A separable buckle including an apertured frame provided with oppositely alined fulcrum pockets offset with respect to the longitudinal center of the frame, a strap, a strap tensioning lever fulcrumed in 130

said pockets and comprising a tensioning bar bent upon itself to engage the end of the strap and form a rounded edge adapted to engage said strap when passed between the lever and frame, said bar being substantially the same width as the strap and having the rounded edge spaced away from the side edges of the wall surrounding the frame aperture a sufficient distance to permit the strap to pass freely between the tension bar and frame when said lever is in open position.

6. In a separable easily mountable two part buckle comprising an apertured frame having a pair of oppositely alined fulcrum pockets, a strap tensioning lever having pintles fulcrumed in said pockets, and a strap crimping bar, said pockets being laterally offset with relation to the longitudinal

center of the frame aperture and depressed 20 a substantial distance below the lower face of the frame, whereby the width of said aperture may be comparatively small but permit the crimping edge of said bar to clear the adjacent edge of the aperture wall 25 as the lever is swung, and the strap may be freely slid between the end of the lever and the frame when the lever is in open position and snugly crimped and held in the aperture when the lever is in closed position. 30

In testimony whereof I hereunto set my hand in the presence of two subscribing witnesses.

ALBERT T. VAN ALSTYN.
